METAL HEATING FURNACE

Frederick S. Bloom, Mount Lebanon Township, Allegheny County, Pa. (6% Bloom Engineering Co. Inc., 857 W. North Ave., N.S., Pittsburgh 33, Pa.)
Filed May 31, 1960, Ser. No. 32,934
3 Claims. (Cl. 266—5)

This invention relates to metal heating furnace apparatus to remove skid marks on pieces of heated work and, further, to compensate for furnace demands or work holdups therein. More particularly, this invention pertains to radiant heating means to selectively heat metal workpieces above the skid mark streaks therein for removal thereof; and, further, to provision and utilization of radiant burner heating means at least in the soaking zone of a furnace to flexibly control the temperature of workpieces therein.

In the heating of heat treating of metal work such as slabs, billets, plates, bars, ingots and other shapes of steel and other metals, numbers of furnaces for that purpose support the work on longitudinally extending rails within the furnace. One conventional way of advancing such work through the furnace is by pushing each entering piece of work into the entry end of the furnace causing it to engage and push forward the line of workpieces up ahead which are already undergoing heating, the foremost piece in such line being discharged contemporaneously with and by the entry of a fresh workpiece. Generally, such furnaces have a plurality of longitudinally spaced zones for heating control of the work respectively in such zones at a particular time. At the end of the heating zones, there is usually provided a soaking section having a hearth along which the workpieces move while they soak to mitigate temperature differentials, e.g., between surface and center or edges and center. However, colder longitudinally extending skid marks remain even though some differential temperature amelioration therein takes place in the course of the soaking and conveying of the heated workpiece after it leaves the furnace. Such colder skid mark streaks are detrimental, particularly with relatively heavier sections, or high capacity and forging practices, or precise thin gauge rolling, which such workpieces may undergo following such heating or heat treatment.

Moreover, in such a furnace, when the mill demand is great and one endeavors to push work therethrough as fast as possible, conventional practices commonly are unable to respond in full correspondence with the heating demand and some temperature unevenness or deficiency may result. On the other hand, when there is a holdup in the furnace due to mechanical furnace troubles or mill delay, even though the firing rate of the burners in the heating zones may be cut back, there may be overheating of the steel therein coupled with a need to maintain such of the work as there is in the soaking zone at rolling temperature.

My invention comprehends apparatus whereby such skid marks are removed by selective application of radiant burner heating to the portions of the workpieces directly above the skid mark streaks. Further, such radiant burners are provided in regular columns and rows in at least a portion of the roof of the soaking zone whereby, additionally, flexible temperature control of the workpieces as a whole is obtainable by uniform or selective regulation of such rows of such radiant heating means to get the work to a predetermined temperature before its discharge from the furnace.

Other objects, features and advantages of this invention will be apparent from the following description and from the accompanying drawings, which are illustrative only, in which

2

FIGURE 1 is a longitudinal section of a rear portion of a slab heating furnace comprising one embodiment of my invention;

FIGURE 2 is a view in section taken along line II—II of FIGURE 1; and,

FIGURE 3 is a view, similar to that shown in FIGURE 1, of another embodiment of this invention.

Referring to FIGURES 1 and 2 of the drawings, there is shown therein a heating furnace 10 through which slabs 11 of metal, such as steel, are pushed through one or more upper and lower heating zone sections 12 and 13, extending to the front of the furnace. Such slabs are intermittently pushed in the direction of arrow 14 and may dwell between movement intervals substantially in the position shown. Soaking of the work 11 in a soaking zone section 15 occurs before they are discharged through a discharge door 16 by gravity. Each heated and soaked slab 11 at the front of the line of workpieces is pushed onto a slide 17 in which water-cooled slide bars 18 may be partially embedded to cause the slab being discharged to engage and swing door 16 open by gravity before the discharged slab slides onto an apron 19 and adjacent equipment such as a roller table, conveyor or manipulator for transferring the discharged heated slab 11 to the next operation to be performed thereon, such as rolling in a roughing mill.

The heating section 12 is provided with a refractory roof 20 and side walls, while soaking section 15 is provided with a horizontal refractory roof 21 which rises to the rear at 22 as shown in the illustrated embodiment and refractory side walls 23, all usually inside of a metal furnace shell or binding. Upper heating compartment or section 12 and a lower heating compartment or section 13 may be heated by one or more direct firing burners 25 each of which fires through a port 26 in a port block 27 set in such end walls. In section 13, similar heating may be provided by burners firing through one or more such port blocks 28.

As the slabs 11, or other metal workpieces, move forward through the furnace, they are supported upon longitudinally extending skid rail supports 29 generally in the form of metal tubes through which cooling water is circulated. Such rails 29 are covered with refractory insulation usually and preferably have an upstanding skid strip 30 on which slabs 11 directly slide and rest. A plurality of such rails 29 are preferably in parallel longitudinally extending arrangement so that different widths and shapes of metal work may be heated in furnace 10, usually with one form of such work being put through at a particular time in accordance with the furnace production schedule. The longitudinally extending rails are further supported by water cooled cross supports 31 made of metal tubing fastened to the rails 29. The cross supports 31 preferably are also insulated to minimize loss of heat to the coolant. Slabs leaving the rearmost portions of the rails 29 pass onto a horizontal solid refractory hearth 24 which may have an upper more highly refractory layer 32 and wear bars 33 inserted in discontinuous overlapping fashion therein to reduce the attrition of the refractory itself by the passage of workpieces 11. Predetermined furnace temperature may be maintained in soaking section 15 by one or more burners 34 extending into the rear of a suitable port block in end wall 35 of that section. In general, in a furnace of the class of furnace 10, burner gases are exhausted by flow in the direction of arrow 36 to a flue located toward the front of the furnace, or otherwise positioned.

Roof area 21 is provided with a series of vertical openings 37 therethrough in a regular pattern. Refractory port blocks 38 are positioned in the openings 37 and preferably are provided with widely flaring port surfaces 39, which surface provides a radiant burner heating sur-

face, which is a surface of revolution having an axis normal to hearth 24. A direct firing radiant burner 40 closes the central opening through each port block 38 and discharges fuel and combustion air generally laterally along the surface 39 of the port block for combustion of such fuel and air in a high thermal release manner causing the surface of the port block facing the work 11 to incandesce at relatively high temperature and selectively heat the workpiece portion exposed to a particular radiant burner. The area on the work "seen" by a particular burner is more highly heated because of the thermal radiation transmitted to the work in general accordance with the Stefan-Boltzmann law.

The openings 37 in the embodiment shown in FIGURES 1 and 2 are arranged in longitudinally extending parallel columns. The respective axes of each are in vertical parallel planes containing the respective longitudinally extending skid rail supports 29. Hence, such columns, the lateral spacing of which is shown in FIGURE 2, are in longitudinal alignment with those rails and selectively heat the tops of slabs 11 in longitudinally extending strips to a higher intensity directly over the longitudinal skid mark streaks, than the portions of the workpieces alongside such stripes. As a consequence, skid marks resulting from the passage of the workpieces over the supports 29 are compensated for, at least some of the skid marks disappearing during soaking with corresponding temperature equalization as the workpieces continue their passage through the furnace and to the next operation.

Further, the openings 37 and the radiant burners are arranged in longitudinally succeeding transverse rows, the spacing of which is shown in FIGURE 1. Each such transverse row has the ability of being operated at a predetermined firing level of its own depending upon the instrumentation selected by those skilled in the instrumentation art for employment therewith. Each transverse row "sees" a particular cross portion of the workpiece line therebeneath and is capable of providing selective transverse heating of high intensity by radiation, with the greatest heat generally being in the transverse stripe directly under each transverse row, respectively. While such selective transverse heating is made possible by such cross row arrangement of direct firing radiant burners, each of those burners therein is also in a particular column and cooperates in the removal of skid marks therebeneath as aforesaid.

In addition, such transverse rows may be utilized to increase the production of furnace 10 or to compensate for mill delay or mechanical troubles in the furnace equipment causing a holdup therein of workpieces. As an example of such a cooperative functioning of a transverse row of radiant burners, let it be supposed that furnace 10 is working virtually to capacity with heavier pieces of steel in the work line, such as blooms instead of slabs. Such will place a severe load on the heating sections and additional heating as well as soaking can be made to occur in the soaking section 15 by virtue of the radiation character of so much of the thermal head due to each transverse row of radiant burners 40 as the blooms move over hearth 24 during the period of their exposure successively to each transverse row. In this way, there is the desirable flexibility in the heating the steel more or less as desired, and quickly, in the soaking section, in respect of workpieces which are to receive more heat than the quantity imparted in the heating sections to provide a higher work temperature upon discharge than would otherwise prevail. With each transverse row of burners independently regulatable in accordance with suitable available instrumentation, the soaking section 15 can be utilized as a flexible, selective, predetermined temperature control for the work.

Conversely, should workpieces be held up in furnace 10 and have a tendency to become overheated, such tendency can be quickly curbed and controlled again by selective regulation of the transverse rows as by turning down the transverse row nearest heating section 12 to a

lower firing rate and then having rearwardly succeeding transverse rows at respectively higher thermal outputs dependent upon the thermal input needs of the workpiece or workpieces exposed to each transverse row of radiant burners above. Such thermal radiation of radiant burners is fast-acting, intense and quickly increased, or decreased, as the finish temperature needs of the workpieces may require.

As a further example, in the processing of quality steel such as high carbon steel for ball bearing metal, and of many stainless steel grades subject to deterioration if held at high temperatures for too long a time, it normally is desirable to heat such material to temperatures in the neighborhood of 1650° F. and then to raise that temperature as fast as possible to final rolling temperature. Such rise to final rolling temperature can readily be achieved relatively quickly, simply and economically in section 15 by utilization of the radiant burners 40 in roof 21.

The foregoing is illustrative of the wide range and flexibility of temperature control obtainable by a practice of my invention inclusive of the removal of skid marks in the course thereof. In the further embodiment of FIGURE 3, parts corresponding in construction and functioning to parts of the preceding embodiment, are provided with the addition of a prime accent thereto. Thus, in the FIGURE 3 embodiment, the entire roof of soaking section 15' may be horizontal and made either a monolithic cast slab with the radiant burner port block surfaces cast therein, as shown, with a central opening to the outside of the slab for the respective burner 40', or separate port block openings may be provided in such roof 21'. Each burner 40' "sees" a larger area because the flare of the port block cavity terminates substantially flush with the underside of roof 21'. Burners 40' are arranged in transverse rows and longitudinally extending columns as in the case of the preceding embodiment, with, however, the burners being shown closer together and covering substantially the whole of hearth 24'. With a greater number of such burners, temperature control range and flexibility is correspondingly increased.

Various modifications may be made in details of the illustrated embodiment, and other embodiments provided, without departing from the spirit of my invention or the scope of the appended claims.

I claim:

1. In a direct-fired metal heating furnace, apparatus comprising, in combination, a heating section having longitudinally extending parallel cooled skid rail supports therein, a soaking section following said heating section, a refractory hearth in said soaking section, a roof in said section substantially parallel to said hearth and relatively close thereto, a plurality of direct firing radiant burners in said roof with circular flaring port block radiant heating surfaces having axes normal to said hearth, said burners being arranged in longitudinal columns with one such column being in alignment with but longitudinally displaced relation to each said skid rail support respectively, said axes in each column being in a vertical plane passing through its respective skid rail support, said burners further being arranged in longitudinally successive transverse rows, said radiant burner being operable at selective thermal input levels to provide heating to a material extent by radiation in and adjacent their respective planes, whereby heating by said burners in said columns in alignment with said skid rail supports supplies radiant heat downwardly and more intensively in longitudinal stripes to remove skid marks directly under said stripes on the underside of workpieces on said hearth by conduction through said workpieces, and, said transverse rows of burner supply heat in cross alignment further to provide a selected input for workpieces exposed to said rows respectively for temperature control of said workpieces in said soaking section.

2. In a direct-fired metal heating furnace to prepare ferrous or alloy metal shapes for hot rolling or the like, apparatus comprising, in combination, a heating section having longitudinally extending cooled skid rail supports therein, a soaking section following said heating section and having a hearth and a horizontal roof above said hearth, a plurality of direct firing radiant burners in said roof directed toward said hearth and substantially normal thereto, said burners being respectively arranged in longitudinal columns with at least one burner in each column and each such column being in alignment with but longitudinally displaced relation to each said skid rail support, said radiant burners being selectively operable to provide heating to a material extent by radiation in said respective longitudinal columns normal to said hearth, whereby heating by said burners in said columns in alignment with said skid rail supports supplies radiant heat downwardly and more intensively in longitudinal

5

10

15

stripes to remove skid marks substantially directly under said stripes on the underside of workpieces on said hearth by conduction through said workpieces.

3. A direct-fired metal heating furnace as set forth in claim 2 having said burners further arranged in longitudinally spaced transverse rows, whereby said transverse rows selectively heat workpieces exposed thereto respectively for flexible control additionally of the predetermined finish temperature of said workpieces.
